PACKING BOX CONSTRUCTION

Glenn Davidson, Bloomington, Ill.

Application October 19, 1932, Serial No. 638,464

6 Claims. (Cl. 217—12)

This invention relates to certain improvements in the construction of cleated panel packing boxes. A cleated panel box is one the ends, sides, top and bottom of which are made of sheets or panels of plywood, fibre-board or equivalent material, with cleats or strips attached at the edges of at least a portion of the panels, these cleats serving as reinforcing members in holding the panels together in the form of a box. In most cases, the cleats extend around the entire periphery of all the panels. When such a box is assembled, the cleats of adjoining panels are ordinarily nailed together, such nailing being the means of holding the individual panels together in the assembled box. Thus we have a box of which the ends, sides, top and bottom are panels bounded by cleats, the cleats bounding adjacent panels being nailed together in pairs and so form the edges of the box extending intermediate the corners.

When such a cleated panel box, loaded with a shifting load such as textiles, fish, meat and the like, is dropped on a corner, the impact results in a shock wave which exhibits an expansive effect and the tendency is to disrupt one or more of the edges of the box by spreading apart the pair of cleats of which the edge is formed. This separation of the cleats forming the edge of the box takes place in two stages. First, due to the fact that the cleats are more securely anchored at the corners of the box than at intermediate points, the natural tendency of the cleats to bend permits a considerable separation at points intermediate the corners of the box. This will happen regardless of the care used in nailing and even if rosin coated or cement covered nails are used. At the end of the first stage of the separation, the pair of cleats forming the rupturing edge of the box resemble in form two archery bows placed string to string.

The end of the first stage of the separation is reached at or near the deflection limit of the cleats. The second stage may take either of two forms. Either the cleats will tear themselves free from their anchorage to other cleats at their upper end and from their respective panels and separate wide apart at their upper ends, or the cleats will break at the point of their greatest separation. Only the edges radiating from the corner of the box sustaining the impact ordinarily suffer rupture. The remaining edges remain intact.

It is obvious that the second stage of the rupture described above could not have occurred had it not been preceded by the first stage. Nev-

ertheless the fact that the greatest apparent damage occurs during the second stage has induced many users of cleated panel boxes to place some kind of tie at the corners of the box. Because ties placed at the corners of the box do not protect against the first stage of the rupture of the edge of the box, they are in a large measure ineffective.

The only other method of reinforcing cleated panel boxes which has come into general use is that of placing one or more bands of metal tape entirely around the box. This, however, is wasteful of material, and requires excessive handling and time-waste by the final packer.

In accordance with my invention, fundamentally important advantages over both these methods of reinforcing cleated panel boxes may be had. As compared to the construction based on a tie placed at the corner of the box, my invention takes account of the first stage of the rupture of the edge of the box which the tie at the corner does not. As compared to the construction employing bands of metallic tape completely encircling the box, my invention is far more economical of metal and time, and further, if the form of my invention described in detail hereinafter wherein the tie is nailed or otherwise fastened to the remote edge of the cleat, is used, the danger of splitting the cleat is much less than in the case where the nail is driven into the face of the cleat as is necessarily the case with bands completely encircling the box. Furthermore, in a cleated panel box the panels themselves have great tensile strength. Accordingly, in case of the band completely encircling the box, the relatively long sections of the band intermediate the edges serve little or no useful purpose, and I have found that only relatively short sections which serve to bind the two cleats together to form the edge of the box are really effective in preventing the rupture of the edge of the box.

Accordingly, the present invention has among its objects the provision of packing box construction which is resistive against disruption and yet without appreciable increase in weight. Another object is a construction which harmonizes with existing manufacturing methods and standards. Other objects and advantages will appear as the description proceeds.

To the accomplishment of the foregoing and related ends, the invention, then, comprises the features hereinafter fully described and particularly pointed out in the claims, the following description and annexed drawing setting forth certain illustrative embodiments of the inven-

tion, these being indicative however, of but a few of the various ways in which the principle of the invention may be applied.

In said annexed drawing:

- 5 Fig. 1 is a perspective view showing an embodiment of my invention; Fig. 2 is an enlarged detail section taken on a plane substantially indicated by the line II--II, Fig. 1; Fig. 3 is a perspective view of a detail; Fig. 4 is a fragmentary plan view of elements such as may enter into the construction; Fig. 5 is a fragmentary perspective view of a further form; and Fig. 6 is a plan view of another form.

Referring more particularly to the drawing, there is shown a packing box having panels 2 or ends, sides, top, etc. and reinforcement strips or cleats 3 at the edges between corners, each edge presenting a pair of adjacent cleats, each cleat being secured to its corresponding panel, the latter being made for instance of plywood, cellulose board, etc. having suitable strength and lightness. The particular manner of joining the ends of the cleats with the abutting panel portions may vary somewhat in accordance with conditions, but with all constructions where two adjacent reinforcements or cleats form the box edge, the advantages of the invention may be had. Joining the adjacent cleats at some point intermediary of the corners is an inter-cleat tie 4, and one or more of these may be located along the cleat-pair if desired. Such inter-cleat tie may take the form of a metallic strip or tape, which may be anchored to the remote edge of each cleat 3 by suitable means, for instance a nail 5, Fig. 2. Conveniently, such inter-cleat ties may be shaped up in preformed condition as illustrated in Fig. 3, being angularly bent to dimension, and provided with nail-holes 6 at the ends. In some cases, the fastening holes 6 may be applied as a final stage after assembling on the cleats, a suitable burring tool setting the hole and indenting or embedding the metal into the wood sufficiently to anchor it even without application further of a nail. However anchored finally, the inter-cleat ties 4 are placed in position on the edges of the box suitably assembled, and as positioned at points intermediary of the corners are capable of firmly holding the cleats together irrespective of customary stresses incurred in the handling of shipping boxes under ordinary conditions.

As a further means of facilitating construction, I may preliminarily apply the inter-cleat strip 4a, Fig. 4, to the panel piece 2a, the panel piece being of any suitable material, plywood, cellulose or composition board, etc., and the metallic strip 4a anchored in convenient handling position with one end 7 adjacent the edge of the panel piece in such position that the cleat 3 when overlaid in its proper relation as indicated in the dotted line position in Fig. 4, will be in position to allow the strip 4a to be loosened at its end 8 and be bent up around the cleats 3. If desired further, a nail may be driven through the strip or tie into the edge of the cleat 3. Such nail position would come relatively at a point such as indicated by the dotted opening 9. It will be understood that for the temporary positioning of the strip 4a in such preliminary manner, the metal may be simply burred into or embedded into the wood by a burring tool at the points 10, 11, a perforation being formed in the metal and tongues being forced down into the wood.

Instead of preliminarily carrying the metallic strips on the side-elements for the boxes, in some

cases it is preferred to preliminarily provide them on the cleat-elements. As shown in Fig. 5, such metallic strip 4b may be preliminarily held to the cleat 3b by being tacked or burred at its ends 12, 13, and when the cleats are assembled with the rest of the box, the strip 4b may be loosened and swung around, as in dotted line position, and be nailed at the end 12 and again at the other end 13 as finally positioned about the other cleat of the associated pair.

If the metallic cleat-elements be initially in the form of a ribbon or tape of indefinite length, as strips or for instance a roll R, Fig. 6, divided into sections of proper length by lines of partial severance as indicated by the dotted lines s, assembly is greatly facilitated. Pre-formed holes 6c, 10c, may be arranged at consistent spacing, ready for the fastenings. Severance of each tie-length requires no heavy duty cutting tool.

As thus seen, in whatever embodiment, my invention makes possible a box construction of particular strength at otherwise weak points, facilitating efficient, yet light construction wherever packing boxes are required with edge-cleats, whether the side elements be of wood panels, plywood, paper board or other light, convenient material. The box assembler, by having a stock of the suitable reinforce ties in whatever form preferred in accordance with this particular requirements can readily carry out the formation of the boxes without requiring any essential change in manufacturing schedules.

Other modes of applying the principle of my invention may be employed instead of the one explained, change being made as regards the details herein disclosed, provided the features stated by any of the following claims, or the equivalent of such, be employed.

I therefore particularly point out and distinctly claim as my invention:

1. In a construction of the character described, preformed sides and top and bottom having cleats, said cleats being arranged in pairs at the edges between corners when said sides, top and bottom are assembled, and bendable metallic ties connecting adjacent cleats at a point intermediary, said ties being secured to the remote edges of said cleats, said edges being substantially perpendicular to the part to which said cleat is secured.

2. In a construction of the character described, preformed sides and top and bottom having cleats, said cleats being arranged in pairs at the edges between corners when said sides, top and bottom are assembled, and bendable metallic ties having angularly disposed arms and further bent attaching terminals each fastened to a remote edge of a cleat of an adjacent pair at a point intermediary.

3. In a permanent box construction, sides and top and bottom, cleats in pairs at the edges between corners and bendable metallic ties permanently connected to remote edges of adjacent cleats at a point intermediary, said edges being substantially perpendicular to the part to which said cleat is secured.

4. In a permanent box construction, sides and top and bottom, cleats in pairs at the edges between corners and bendable metallic ties of one piece construction permanently connected to remote edges of adjacent cleats at a point intermediary, said edges being substantially perpendicular to the part of which said cleat is secured.

5. In a construction of the character described, a box side and a bendable metallic cleat

tie carried thereby, one end of said tie being secured to said side adjacent an edge thereof and at a substantially intermediate point, and a cleat secured to said side adjacent said edge and overlying said portion of said tie, whereby said tie is firmly anchored and may be bent over said cleat to be secured to a cleat of another side.

5. In a construction of the character described,

a box panel having a cleat secured thereto, one edge of said cleat rising substantially parallel to said panel and a bendable cleat tie rotatably secured to said edge at a substantially intermediate point of said cleat, whereby a series of such panels 5 may be readily assembled into a box.

GLENN DAVIDSON.
